Patented Apr. 7, 1925.

UNITED STATES PATENT OFFICE.

WILLIAM LEONARD HOFER, OF MANHATTAN, KANSAS.

FOUNTAIN PEN.

Application filed September 2, 1924. Serial No. 735,353.

To all whom it may concern:

Be it known that I, WILLIAM LEONARD HOFER, a citizen of the United States, residing at Manhattan, in the county of Riley and State of Kansas, have invented a new and useful Fountain Pen, of which the following is a specification.

This invention relates to fountain pens and the object thereof is to so construct a pen of this character as to obviate the necessity of placing the pen and part of the holder into the ink and avoiding wiping of the pen after filling and the consequent soiled fingers and clothes.

Another object of the invention is to so construct a pen of this character as to avoid jamming the point against the bottom of the ink stand which frequently injures the point and which is so constructed as to drain all of the ink from the bottle.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings—

Figure 1 represents a longitudinal section of the attachment constituting this invention shown applied, the pen being shown in side elevation with parts broken out;

Fig. 2 is a similar view of the attachment detached;

Fig. 3 is a view similar to Fig. 1 showing a slightly different form of the invention;

Fig. 4 is a view similar to Fig. 2 showing the form illustrated in Fig. 3; and

Fig. 5 is a transverse section taken on the line 5—5 of Fig. 1.

In the form shown in Figs. 1 and 2 an ordinary fountain pen barrel is shown at 1 screw threaded at its front end as shown at 2 the point carrying portion of the pen being shown at 3 having a shoulder 4 for a purpose presently to be described.

The attachment constituting this invention comprises a sleeve 10 internally threaded on its rear portion as shown at 11 to engage the threaded portion 2 of the pen barrel 1 when the attachment is in operative position. This sleeve 10 has a reduced

chamber 12 at the front portion thereof to receive and house the pen point 5. A shoulder 13 is formed at the junction of the reduced portion 12 with the main portion or chamber of the sleeve and against which the shoulder 4 of the pen barrel is designed to abut as is shown clearly in Fig. 1.

A bore 14 extends forwardly through the end of sleeve 10 communicating with the chamber 12 and has mounted therein a tubular extension 15 which is designed to protect the pen point when the pen is being filled, said extension being insertable in the ink well for this purpose and it also adapts the device to be used for draining the ink bottle to the last drop.

A removable cap 16 is mounted on the front end of the sleeve 10 and is here shown having threaded engagement with the sleeve. This cap 16 is designed to protect the tubular extension 15 and remains in position on sleeve 10 at all times except when it is desired to fill the pen when said cap 16 is removed and the tube 15 inserted in the ink and the filling operation performed in the usual manner. The means for filling the pen constituting no part of this invention it is thought unnecessary to illustrate it.

The chamber 12 in which the pen point 5 is housed is of sufficient size to permit turning of the sleeve 10 when applying or removing it without damaging the pen point.

When it is desired to fill the pen the small cap 16 is removed and the tube 15 inserted into the ink and the pen filled in the usual manner by compressing the filling device. The cap 16 is then screwed on again and is not removed except when the pen is to be filled. To use the pen the entire cap section or sleeve 10 is removed and placed on the other end of the pen barrel 1 in the usual manner.

The sleeve-like attachment 10 may be easily applied to any make of pen and will obviate the necessity of placing the pen and part of the holder into the ink avoiding wiping the pen after filling.

In Figs. 3 and 4 the attachment 10^a is exactly like the one shown in Figs. 1 and 2 except that the pen point housing chamber 12^a is made tapered toward its front end to conform to the shape of the pen point and merges into the reduced tubular extension 15^a. The other parts are the same and are numbered the same except that

the exponent "a" is used in connection with the reference numerals.

I claim:

1. A fountain pen attachment comprising a sleeve for insertion on a pen barrel and having a chamber to house the pen point with a tube extending longitudinally from the front end of said chamber to facilitate filling of the pen and to protect the point thereof.

2. A fountain pen attachment comprising a sleeve for insertion on a pen barrel and having a chamber to house the pen point with a tube extending longitudinally from the front end of said chamber to facilitate filling of the pen and to protect the point thereof, and a removable cap mounted on said sleeve over said tube.

3. An attachment of the class described comprising a sleeve for insertion on a fountain pen barrel having a reduced pen point receiving chamber at its front end with a shoulder at the rear end of said chamber for abutment by the pen barrel to limit its insertion in said sleeve, and a tubular extension extending from the front of said reduced chamber and communicating therewith.

In testimony that I claim the foregoing as my own, I have hereto affixed my signature in the presence of two witnesses.

WILLIAM LEONARD HOFER.
